UNITED STATES PATENT OFFICE.

JOHN D. FREESE, OF CHICAGO, ILLINOIS.

DESIGN FOR A GAME-TABLE.

SPECIFICATION forming part of Design No. 33,315, dated October 2, 1900.

Application filed August 31, 1899. Serial No. 729,130. Term of patent 3½ years.

To all whom it may concern:

Be it known that I, JOHN D. FREESE, a citizen of the United States of America, and a resident of Chicago, in the county of Cook and State of Illinois, have invented a new and Original Design for Game-Tables, of which the following is a specification, reference being had to the accompanying drawing, forming a part thereof.

5 10 The drawing shows a perspective view of a game-table made according to my new design.

The leading feature of my design consists in the peculiar relative arrangement on the 15 table-top of the pins 13, the pins forming the pockets 7, the partitions 8, and the pockets 3, 4, 5, and 6.

20 The partitions 8 are located on said table-top inwardly from the side pieces of the rim 2, forming the alleys 9. The lower ends of the alleys are filled at 10, said filled parts

having therein grooves 11. The upper part of the rim forms the inner semicircular surface 12.

13 represents a number of single upright pins 25 projecting from the body of the table-top.

Pockets 14 are located at the lower end of the table-top.

15 20 25 30 35 13 represents a box or receptacle projecting from the front of the table, which is supported by the legs 16.

What I claim as new, and desire to secure by Letters Patent, is—

The design for a game-table, substantially as herein shown and described.

Signed by me at Chicago this 29th day of August, 1899.

JOHN D. FREESE.
